United States Patent Office

Des. 182,859
Patented May 20, 1958

182,859

AUTOMOBILE

Charles A. Stebbins, Birmingham, Mich., assignor to General Motors Corporation, Detroit, Mich., a corporation of Delaware

Application February 11, 1957, Serial No. 44,828

Term of patent 7 years

(Cl. D14—3)

Figure 1 is a side elevational view of an automobile embodying my new design;

Figure 2 is a partial top plan view of the rear portion of the automobile; and

Figure 3 is a rear elevational view of the rear portion of the automobile.

The dominant features of my new design reside in the full line portions of the drawing.

I claim:

The ornamental design for an automobile, substantially as shown and described.
